UNITED STATES PATENT OFFICE.

LEWIS S. COX, OF PHILADELPHIA, PENNSYLVANIA.

MANUFACTURE OF STOCKINGS.

SPECIFICATION forming part of Letters Patent No. 250,207, dated November 29, 1881.

Application filed August 15, 1881. (No model.)

To all whom it may concern:

Be it known that I, LEWIS S. COX, a citizen of the United States, residing in Philadelphia, Pennsylvania, have invented an Improvement 5 in Stockings, of which the following is a specification.

The object of my invention is to make a "cut stocking" of better shape, of more uniform elasticity throughout the leg, ankle, and heel portions, and more comfortable to the wearer than ordinary stockings of this class. This object

I attain in the manner which I will now proceed to describe, reference being had to the accompanying drawings, in which—

15 Figure 1 is a view illustrating the ordinary mode of making "cut hose," and Fig. 2 a view showing my improved stocking and mode of making the same.

Prior to my invention the common mode of 20 making cut hose was to knit a narrow tube of a fabric of about the same diameter as the ankle portion of the desired stocking, to form the heel and foot of a piece of the tube by cutting, folding, and sewing, so as to make the stocking-blank, Fig. 1, which has a cylindrical leg. The next step was to convert this leg and the heel into the proper shape, and this was done by drawing the stocking-blank over a press-board or former, so as to distend the tube at 25 the calf, heel, and foot, as indicated by dotted lines in the said figure, and, finally, to induce the stocking to retain the shape to which it had been thus stretched by heat and pressure. This, of course, is an imperfect stocking, as it 30 is not of the same elasticity throughout, the ankle portion, which has not been stretched, being elastic enough, but the fabric at the calf and heel being deprived (more or less) of its elasticity by stretching the tube on the former.

40 I discard this old plan of making cut hose, and use a knitted tube of the same diameter as the upper portion of the leg of the desired stocking, A, Fig. 2, being the portion of the tube for the leg of the stocking, and the lower portion 45 of the tube being converted into the heel and

foot of the stocking, preferably according to the plan described in the patent of J. H. Osborne, No. 242,684, June 7, 1881. A stocking-blank is thus formed which has more fabric than is necessary, and I proceed to remove this 50 surplus fabric by cutting the blank on the dotted line *m*, Fig. 2, and finally unite the severed edges by means of a sewing or seaming machine, the line on which the fabric is severed reducing the leg and heel of the stocking to 55 the desired shape.

By my improvement I produce a stocking of the proper shape without resorting to the usual stretching, and the stocking, being of uniform elasticity throughout, is a cheap and acceptable substitute for the more expensive stockings, which are known in the trade as "full fashioned" or "full regular made," and which are made by the tedious and costly process of varying the width of the fabric in the machine 60 during the process of knitting.

I claim as my invention—

1. The improvement in the manufacture of cut stockings, which consists in first making a stocking-blank the leg of which consists of an 70 unbroken or continuous tube of knitted fabric of the same diameter as the upper portion of the leg of the desired stocking, then cutting away the rear of the tube to the desired shape of the calf, ankle, and heel, and finally seaming the severed edges, all substantially as set forth.

2. As a new article of manufacture, the within-described cut and seamed stocking, in which the upper portion of the leg is composed of an 80 unbroken tube, and the calf, ankle, and heel are formed by cutting and seaming said tube at the rear, as set forth.

In testimony whereof I have signed my name to this specification in the presence of two subscribing witnesses.

LEWIS S. COX.
